FRED DEBNAY, OF MILWAUKEE, WISCONSIN.

ATTACHMENT FOR SINKS.

1,411,684.

Specification of Letters Patent. Patented Apr. 4, 1922.

Application filed March 25, 1921. Serial No. 455,594.

To all whom it may concern:

Be it known that I, FRED DEBNAY, a citizen of the United States, residing at Milwaukee, county of Milwaukee, and State of Wisconsin, have invented new and useful Improvements in Attachments for Sinks, of which the following is a specification.

This invention relates to attachments for sinks.

10 As is well known, sinks are usually at a uniform height which is as a rule too low for the average user. It therefore requires a considerable amount of bending and useless expenditure of energy to wash articles 15 in the average sink. It is to overcome these defects that the present invention is designed.

The primary objects of this invention are to provide a device which may be placed 20 within a sink and is adapted to hold the dishpan or other utensil at a convenient height for the operator; and to provide such a device which is readily adjustable in height to meet various requirements.

25 Further objects are to provide a device which may be placed within a sink and which is provided with a removable screen or other porous partition; which may be readily and cheaply manufactured; and 30 which is composed of a minimum number of parts.

Embodiments of the invention are shown in the accompanying drawings, in which:

Fig. 1 is a side view partly in section of 35 the device in its shortest position of adjustment.

Fig. 2 is an end view thereof.

Fig. 3 is a plan view.

Fig. 4 is an end view partly in section 40 showing the attachment in another position of adjustment and positioned within a sink.

Fig. 5 is a detail of the adjusting means.

Fig. 6 is a fragmentary view showing a modified form of construction for the screen 45 supporting portion.

The device comprises a substantially box-like structure 1 which tapers towards the lower edge and is provided with a beaded upper edge 2. This boxlike structure is open 50 top and bottom and may conveniently be formed of a single piece of suitably shaped material, such for example, as sheet metal. Intermediate its upper and lower edges a fold 3 is formed in the sheet material and 55 is projected inwardly. This fold forms a narrow ledge extending inwardly and pass-

ing completely around the inner periphery of the device. Upon this ledge, a wire or other screen 4 rests. This screen may conveniently be formed with a wire reenforcing border 5 which seats upon the projection 3. It is removable and is therefore very easy to clean.

The height of the apparatus may be varied with reference to the bottom 6 of the sink by means of the angle iron legs 7. These legs are provided at each of the four corners of the device and are equipped with a plurality of uniformly spaced holes 8. A bolt 9 extends outwardly at each of the corners through the wall of the device and is provided with a wing nut 10 so that after such bolt has been passed through the appropriate opening 8 of one of the legs, the wing nut is then screwed into place and securely locks the leg against the boxlike structure.

A convenient and effective way of securing the bolt to the body portion is illustrated in detail in Fig. 5. At the corners 80 of the device, the inwardly projecting ledges 3 or folded portions are overlapped and the right angled extension 14 of the bolt is passed upwardly through such overlapping portions and is provided with an enlarged 85 head 15. This construction securely positions the bolt and prevents its turning when the wing nut 10 is operated. In addition to this, it serves as a reenforcing and locking means to securely fasten adjacent overlapping ledges 3 together thereby adding to the rigidity of the structure.

In the preferred form as described above, the device is formed of sheet iron and is enameled. However, it may be desirable in 95 cheaper forms of the invention to make it of galvanized iron. In this case, the construction would be substantially like that previously described with, however, the omission of the ledges 3. In place of these 100 ledges a series of projecting tongues 13 are positioned at spaced points about the inner portion of the rectangular structure and serve as a suitable support for the wire or other screen 4 as illustrated in Fig. 6. These 105 projections may be formed integrally by bending cut out portion inwardly or they may be formed of relatively small pieces with a downwardly extending right angled extension which may be securely fastened to the body portion 1 by soldering, brazing, or riveting or in any suitable manner.

In all forms of the invention, handles 11 may be provided at each end of the device so that it may be readily lifted out or adjusted in the sink. If desired, the bottom or foot 5 portion of the leg 7 may be equipped with resilient pads 15, preferably of rubber, so that these legs will not scratch the enameled portion of the sink.

It will thus be seen that a simple and 10 effective device has been provided which may be readily adjusted to properly position the utensils at the desired height for the operator. Inasmuch as the setting of the sinks is uniformly too low for the average person 15 and inasmuch as the setting is substantially at one height for all sinks, the adjustability in height of this device contributes markedly to the comfort of the operator.

It will further be noted that when the wire 20 screen is removed it may be readily cleaned and that the remaining portion consists simply of an open boxlike structure which may also be readily cleaned.

I claim:

25 1. An attachment for sinks comprising a boxlike member having open top and bottom, supporting means extending inwardly intermediate the top and bottom of said member, bolts anchored in said supporting 30 means and extending outwardly through the

walls of said boxlike member at each of the corners thereof, and a plurality of legs positioned at each corner and provided with a plurality of openings through any one of which the corresponding bolt is adapted to 35 pass and nuts for clamping the legs in position.

2. An attachment for a sink comprising a sheet metal box-like member open top and bottom and provided with an integrally inwardly folded series of ledges having overlapping portions, a series of bolts passing through and anchored to the overlapping portions of such ledges and extending outwardly through the wall of said boxlike 45 member, a series of perforated angle shaped legs positioned at the corners of said boxlike member with certain of the perforations aligning with the corresponding bolts, and nuts for clamping the legs in position. 50

3. An attachment for a sink comprising a boxlike member open top and bottom, a partition removably carried within said member, a plurality of legs extending downwardly from said member and adapted for 55 relative motion of adjustment with respect to said member, and means for clamping said legs in adjusted position.

FRED DEBNEY.
